UNITED STATES PATENT OFFICE

WILLIAM B. GRIFFITH, OF AUDUBON, NEW JERSEY, ASSIGNOR TO STAR SPRINKLER CORPORATION, OF PHILADELPHIA, PENNSYLVANIA, A CORPORATION OF NEW JERSEY

ALARM VALVE FOR SPRINKLER SYSTEMS

Application filed December 12, 1929. Serial No. 413,468.

My invention relates to an alarm valve adapted for sprinkler systems for the protection of buildings against fire.

In sprinkler systems it is the common practice to employ an alarm valve through which the water is supplied to the system, and an alarm device which is operated by the water pressure passing through the valve when the same is opened by the system being opened and brought into operation. Heretofore it has been necessary to employ a separate retarding device which was interposed between the valve and the alarm device for preventing the premature operation of the latter, due to fluctuations or water hammer in the water supply pressure, which would cause the valve to prematurely open and operate the alarm device before the system was opened for operation upon the occurrence of fire in the building.

The object of my invention is to construct the main or alarm valve of the system for operating an alarm device in such a manner that a separate retarding device is unnecessary; a further object is to provide the valve clapper with a movable member or diaphragm which is presented toward the supply pressure side of the valve, and which is adapted to yield when the supply pressure is suddenly increased thereby reducing the tendency of the clapper to open and actuate the alarm device prematurely; a further object is to provide the clapper with pumping mechanism, which is actuated by the fluctuations in the supply pressure, for building up the pressure and for maintaining the increased pressure above the clapper, so that the relatively greater pressure above the clapper will hold it closed against sudden fluctuations in the supply pressure below the clapper.

These together with various other novel features of construction and arrangement of the parts, which will be more fully hereinafter described and claimed constitute my invention.

Referring to the accompanying drawing the figure represents a central vertical sectional view of an alarm valve showing diagrammatically a water motor alarm device

and an electric circuit closer, for operating an alarm device, operatively associated with the alarm valve.

In the drawing in which like reference characters refer to like parts, a valve casing 1 is shown having an inlet opening 2 and an outlet opening 3. A supply pipe 4 is connected with the inlet opening 2 for supplying water under pressure from a street main or any other source of supply. An outlet pipe or riser 5 is connected with the outlet 3 of the casing. Said pipe 5 forms part of the sprinkler system, not shown in the drawing, in which the pipe 5 is connected with branch pipes closed by sprinkler heads which are adapted to open automatically by an increase of temperature upon the occurrence of a fire in the building in which the system is installed.

Within the valve casing 1 is provided a valve seat 10 which surrounds the main passageway through the casing 1 from the inlet 2. A valve clapper 12 is mounted upon an arm 14, which is pivoted upon a shaft 15 secured in the casing, and adapted to move to and from the valve seat 10. When the clapper 12 is closed upon the seat 10 an inlet chamber 16 is formed within the casing 1 below the clapper and an outlet chamber 18 is formed within the casing above the clapper.

A yieldable member 20 is secured upon the under side of the clapper 12 by means of a clamp ring 21, secured by bolts 22 to the clapper. The peripheral portion of the member 20 forms a facing or gasket which is interposed between the clapper 12 and the valve seat 10 adapted to form a tight joint between the clapper and the valve seat.

The valve seat 10 is in the form of a sleeve which is detachably secured by means of a screw thread 23 formed thereon, which engages a similar thread formed within the casing 1. Upon the face of the valve seat 10 is provided an annular groove or channel 24, which extends lengthwise through the sleeve forming said valve seat 10 and communicates with a recess 25 formed in the casing 1, with which recess a pipe 26 is connected. The pipe 26 is connected with

branch pipes 27 and 28. An electric circuit closer 30 is connected with the pipe 27 so that when water pressure is admitted through the groove 24 in the valve seat 10, 5 due to the lifting of the clapper 12 an electric bell or any suitable signal device will be operated, in a manner well known in the art. The pipe 28 is connected with a water motor 31, which will operate a bell or signal device 32 simultaneously with the operation of the device 30 for the purpose of giving an additional alarm.

The clapper 12 has formed therein a cavity 35 upon the under face thereof adjacent 15 to the inlet chamber 16. The opening of said cavity 35 adjacent to the chamber 16 is closed by a movable member 36, which in the present embodiment is shown in the form of a flexible diaphragm secured to the 20 clapper by the clamp ring 21. The diaphragm 36 may be made in one piece with the gasket 20 for convenience.

The movable member or diaphragm 36 is preferably made of flexible material so 25 that it will readily flex from the position shown in full lines to the position shown in dotted lines. Upon the central portion of the diaphragm is secured a check valve 40 comprising a body portion 41 and a clamp 30 portion 42 adapted for securing the central portion of the diaphragm 36 between them. A central opening or port 43 is formed 35 through the check valve body 41 and is adapted to be closed by means of a ball check 44, which engages a seat 45, and permits the free passage of pressure from the chamber 16 into the cavity 35 and prevents the escape of pressure from the cavity 35, in the reverse direction, into the chamber 16.

A spring 46 is located within the cavity 35 and is adapted for moving the diaphragm 36 into the normal position shown in full lines in which the body portion 41 rests 45 upon a stop in the form of inwardly projecting fingers 48, formed upon the clamp ring 21. The clapper 12 is provided with a central opening or port 50, and a valve seat 51 at the lower end of said port, upon which 50 seat a ball check 52 normally rests for allowing a relatively higher pressure to freely pass from the cavity 35 into the outlet chamber 18, thus preventing the pressure from returning from the chamber 18 to the cavity 35.

The operation of my invention is as follows: Water pressure is admitted to the inlet chamber 16, which passes through the port 43 into the cavity 35 and through the 60 port 50 into the outlet chamber 18, thus filling the system through the pipe 5.

Air is trapped in the system at the ends of the branch pipes connected with the pipe 5, and as the pressure varies in the chamber 65 18 and in the branch pipes the trapped air

compresses and expands in response to water hammer in the supply pipe 4, thus permitting the flexible portion 36 of the diaphragm to be flexed against the pressure of the water in the chambers 35 and 18.

The flexible portion of the diaphragm 36 is smaller in area than the area of the passageway or opening through the valve seat 10 and the pipe 2, therefore when a sudden increase of the water pressure in the inlet 70 chamber 16 occurs, the diaphragm 36 will yield or flex before the pressure will lift the clapper 12 from its seat, thus reducing the tendency of the clapper 12 to open.

The repeated flexing of the diaphragm or member 36 will act as a pump, so that the successive variations in the water pressure in the inlet chamber 16, caused by sudden impulses of pressure in the supply pipe, will cause the diaphragm 36 to pump the pressure into the outlet chamber 18, thus causing a greater pressure to be accumulated in the chamber 18 above the clapper than the normal pressure below the clapper. The increased pressure in the chamber 18 will hold the clapper closed against sudden impulses of pressure which may occur in the supply pipe and in the inlet chamber 16.

When a sudden increase of pressure in the inlet chamber 16 occurs the diaphragm 36 will be flexed and force the water from the cavity 35 through the port 50 into the chamber 18, thereby increasing the pressure in the chamber 18. The spring 46 will return the diaphragm 36 to the position shown in 90 full lines.

The ball check 52 will retain the increased pressure in chamber 18, and the ball check 44 will retain the increased pressure in the cavity 35. Upon each successive flexing of the diaphragm 36 the pressure will gradually be increased in the chamber 18 until it is much greater than the normal pressure in the inlet chamber 16. This increased pressure in the chamber 18 will hold the clapper 12 closed upon its seat against a sudden high increase of pressure in the supply pipe and in the chamber 16, due to water hammer in the street main or supply pipe, thus holding the clapper 12 upon its seat, and preventing the water passing through the groove 24 and the pipe 26 and operating the alarm devices.

When a sprinkler head opens, the pressure in the outlet chamber 18 will be reduced so that the pressure in the inlet chamber 16 will open the clapper 12, thus allowing the water pressure to pass through the annular groove 24 in the valve seat 10 so that the pressure may pass through the pipe 26 and operate the alarm devices in the usual manner.

Various other changes in construction and the arrangement of the parts may be made without departing from my invention.

I claim:

1. A valve casing having inlet and outlet chambers formed therein, a valve seat upon the casing surrounding a passageway connecting said chambers, a valve clapper movable to and from said seat for separating said chambers when closed upon the seat, said clapper having a greater surface exposed to the pressure in the outlet chamber than the surface thereof exposed to the pressure in the inlet chamber, means for slowly admitting pressure from the inlet chamber to the outlet chamber, said means including a flexible member mounted upon said clapper, said member having a portion located in spaced relation with the clapper, said member having one face thereof presented to said inlet chamber, means forming a communication between the inlet chamber and the space between said member and the clapper, means forming a communication between said space and the outlet chamber, said member arranged to yield before the clapper is lifted from its seat upon a sudden increase of pressure in the inlet chamber, an alarm device, and means operatively associated with the clapper for actuating the alarm device when the clapper is lifted from its seat.
2. A valve casing having inlet and outlet chambers formed therein, a valve seat upon the casing surrounding a passageway connecting said chambers, a valve clapper movable to and from said seat for separating said chambers when closed upon the seat, said clapper having a greater surface exposed to the pressure in the outlet chamber than the surface thereof exposed to the pressure in the inlet chamber, a flexible member mounted upon the clapper, said member having a central portion of smaller area than said passageway surrounded by the valve seat arranged in spaced relation to the clapper and having a surface presented to the inlet chamber adapted to yield before the clapper is lifted from its seat by a sudden increase of pressure in the inlet chamber, said member having a passageway formed therethrough forming a communication from the inlet chamber to the space between said member and the clapper, said clapper having a passageway communicating between said space and the outlet chamber, an alarm device, and means operatively associated with the clapper for actuating the alarm device when the clapper is lifted from its seat.
3. An alarm valve for sprinkler systems having in combination a valve clapper movable to and from a seat and forming inlet and outlet chambers within the valve, said clapper having a greater surface exposed to the pressure in the outlet chamber than the surface thereof exposed to the pressure in the inlet chamber, said clapper

having a cavity formed therein the open end of which is presented toward said inlet chamber, said clapper having a port formed therein forming a passageway between said cavity and said outlet chamber, a flexible member upon the clapper separating the open end of said cavity from said inlet chamber, and said member having an opening formed through the same communicating between the inlet chamber and said cavity, and said member adapted to flex upon a sudden increase of pressure within said inlet chamber prior to the opening of the clapper.

4. A valve casing having inlet and outlet chambers formed therein, a valve seat upon the casing surrounding a passageway connecting said chambers, a valve clapper movable to and from said seat for separating said chambers when closed upon the seat, said clapper having a greater surface exposed to the pressure in the outlet chamber than the surface thereof exposed to the pressure in the inlet chamber, said clapper having a cavity formed therein the open end of which is presented toward said inlet chamber, said clapper having a port formed therein forming a passageway between said cavity and said outlet chamber, a flexible member upon said clapper separating the open end of said cavity from said inlet chamber, and said member having a port formed therein through which the pressure may slowly pass from the inlet chamber to the outlet chamber and a sudden increase of pressure in the inlet chamber will flex said member and reduce the tendency of the pressure to open the clapper, said valve seat having an aperture formed therein arranged to be closed by the clapper when upon its seat and opened when the clapper is lifted from its seat, and an alarm device operatively associated with said aperture in the valve seat.

5. A valve casing having inlet and outlet chambers formed therein, a valve seat upon the casing surrounding a passageway connecting said chambers, a valve clapper movable to and from said seat for separating said chambers when closed upon the seat, said seat having an aperture formed therein closed by the clapper when upon said seat, an alarm device operatively connected with said aperture formed in said seat adapted to be opened when the clapper is raised from its seat, means upon the clapper for slowly admitting pressure from the inlet chamber to the outlet chamber when the clapper is closed upon its seat, a flexible member upon said clapper having a portion thereof in spaced relation with the clapper, said clapper having a port formed therein communicating between the space formed between said member and the clapper and the outlet chamber, said member having one surface thereof presented to

- wards the inlet chamber and arranged and positioned to yield under a sudden increase of pressure in the inlet chamber before the clapper is lifted from its seat, said member 5 having a port formed therein, and a check valve upon said member arranged to close said port against the passage of liquid toward the inlet chamber.
6. A valve casing having inlet and outlet 10 chambers formed therein, a valve seat upon the casing surrounding a passageway connecting said chambers, a valve clapper movable to and from said seat for separating said chambers when closed upon the seat, 15 means upon said clapper actuated by variations of pressure in the inlet chamber due to impulses in the source of supply for pumping pressure from the inlet chamber into the outlet chamber, means operable to 20 maintain a relatively higher pressure in the outlet chamber for holding the clapper closed upon its seat against the action of a sudden increase of pressure in the inlet chamber, said valve seat having an aperture 25 formed therein arranged to be closed by the clapper when upon its seat and opened when the clapper is lifted from its seat, and an alarm device operatively associated with said aperture in the valve seat.
- 30 7. A valve casing having inlet and outlet chambers formed therein, a valve seat upon the casing surrounding a passageway connecting said chambers, a valve clapper movable to and from said seat for separating said chambers when closed upon the seat, 35 a movable member upon said clapper actuated by variations of pressure in the inlet chamber due to impulses in the source of supply arranged to pump pressure from the 40 inlet chamber into the outlet chamber, a check valve upon the clapper for maintaining a relatively greater pressure within said outlet chamber than the normal pressure in said inlet chamber, said valve seat having 45 an aperture formed therein arranged to be closed by the clapper when upon its seat and opened when the clapper is lifted from its seat, and an alarm device operatively associated with said aperture in the valve 50 seat.
8. A valve casing having inlet and outlet chambers formed therein, a vale seat upon the casing surrounding a passageway connecting said chambers, a valve clapper movable to and from said seat for separating said chambers when closed upon the seat, said clapper having a greater surface exposed to the pressure in the outlet chamber than the surface thereof exposed to the pressure in the inlet chamber, said clapper having a cavity formed therein the open end of which is presented towards said inlet chamber, said clapper having a port communicating between said cavity and the outlet chamber, a flexible member upon said 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930
- clapper separating the open end of said cavity from said inlet chamber, said member having a passageway formed therethrough communicating between the inlet chamber and said cavity, a spring located in said cavity tending to flex said member towards said inlet chamber and permit said member to yield under a sudden increase in pressure in the inlet chamber before the clapper is lifted from its seat, said valve seat having an aperture formed therein arranged to be closed by the clapper when upon its seat and opened when the clapper is lifted from its seat, and an alarm device operatively associated with said aperture in the valve seat.
9. A valve casing having inlet and outlet chambers formed therein, a valve seat upon the casing surrounding a passageway connecting said chambers, a valve clapper movable to and from said seat for separating said chambers when closed upon the seat, a check valve upon the clapper for admitting pressure from the inlet chamber to the outlet chamber and retaining it in the latter, a flexible member upon the clapper, said clapper having a cavity, of smaller area than said passageway surrounded by said valve seat, said flexible member positioned between the cavity formed in the clapper and the inlet chamber arranged to force pressure from said cavity through the check valve into the outlet chamber when flexed by a sudden increase of pressure in the inlet chamber, said member having a port formed therein, a check valve upon said member arranged to close said port against the return of liquid from said cavity to the inlet chamber, said valve seat having an aperture formed therein arranged to be closed by the clapper when upon its seat and opened when the clapper is lifted from its seat, and an alarm device operatively associated with said aperture in the valve seat.
10. A valve casing having inlet and outlet chambers formed therein, a valve seat upon the casing surrounding a passageway connecting said chambers, a valve clapper movable to and from said seat for separating said chambers when closed upon the seat, said clapper having a cavity formed therein the open end of which is presented towards said inlet chamber, said clapper having a port formed therein forming a passageway between said cavity and said outlet chamber, a flexible member upon said clapper separating the open end of said cavity from said inlet chamber, said flexible member having a port formed therein forming a restricted passageway between said inlet chamber and said cavity, a check valve for automatically closing said port formed in the clapper against the return passage of a pressure medium from the outlet chamber into said cavity, said valve seat having an aperture formed therein arranged to be

closed by the clapper when upon its seat and opened when the clapper is lifted from its seat, and an alarm device operatively associated with said aperture in the valve seat.

5 11. A valve casing having inlet and outlet chambers formed therein, a valve seat upon the casing surrounding a passageway connecting said chambers, a valve clapper movable to and from said seat for separating said chambers when closed upon the seat, said clapper having a cavity formed therein the open end of which is presented toward said inlet chamber, said clapper having a port formed therein forming a passageway 70 between said cavity and said outlet chamber, a flexible member upon said clapper separating the open end of said cavity from said inlet chamber, said flexible member having a port formed therein forming a restricted passageway between said inlet chamber and said cavity, a check valve for automatically closing said port formed in the clapper against the return passage of a pressure medium from the outlet chamber 75 into said cavity, a stop upon said clapper for limiting the movement of said member toward said inlet chamber, a spring within said cavity tending to flex said member toward said inlet chamber, said valve seat having an aperture formed therein arranged to be closed by the clapper when upon its seat and opened when the clapper is lifted from its seat, and an alarm device operatively associated with said aperture in the valve seat.

12. A valve casing having inlet and outlet chambers formed therein, a valve seat upon the casing surrounding a passageway connecting said chambers, a valve clapper movable to and from said seat for separating said chambers when closed upon the seat, said clapper having a cavity formed therein 80 the open end of which is presented toward said inlet chamber, said clapper having a port formed therein forming a passageway between said cavity and said outlet chamber, a flexible member upon said clapper separating the open end of said cavity from said inlet chamber, said flexible member having a port formed therein forming a passageway between said inlet chamber and said cavity, a check valve for automatically closing said port formed in the valve against the return passage of a pressure medium from the outlet chamber into said cavity, a stop upon said clapper for limiting the movement of said member toward said inlet chamber, said valve seat having an aperture formed therein arranged to be closed by the clapper when upon its seat and opened when the clapper is lifted from its seat, and an alarm device operatively associated with said aperture in the valve seat.

13. A valve casing having inlet and outlet chambers formed therein, a valve seat upon the casing surrounding a passageway connecting said chambers, a valve clapper movable to and from said seat for sepa-

rating said chambers when closed upon the seat, said clapper having a cavity formed therein the open end of which is presented toward said inlet chamber, said clapper having a port formed therein forming a passageway between said cavity and said outlet chamber, a flexible member upon said clapper separating the open end of said cavity from said inlet chamber, said flexible member having a port formed therein forming a restricted passageway between said inlet chamber and said cavity, a check valve for automatically closing said port formed in the clapper against the return passage of a pressure medium from the outlet chamber 80 into said cavity, a stop upon said clapper for limiting the movement of said member toward said inlet chamber, a spring located upon the clapper for normally holding said member against said stop, said valve seat 85 having an aperture formed therein arranged to be closed by the clapper when upon its seat and opened when the clapper is lifted from its seat, and an alarm device operatively associated with said aperture in the valve seat.

14. A valve casing having inlet and outlet chambers formed therein, a valve seat upon the casing surrounding a passageway connecting said chambers, a valve clapper movable to and from said seat for separating said chambers when closed upon the seat, an alarm device operatively connected with said casing adapted to be operated when the clapper is raised from its seat, said clapper having a cavity formed therein the open end of which is presented towards said inlet chamber, said clapper having a port formed therein forming a passageway between said cavity and said outlet chamber, a flexible member upon said clapper separating the open end of said cavity from said inlet chamber, said flexible member having a port formed therein forming a passageway between said inlet chamber and said cavity, a check valve for automatically closing said port formed in the clapper against the return passage of a pressure medium from the outlet chamber into said cavity, a check valve for automatically closing said port formed in said member against the return passage of pressure medium from said cavity into the inlet chamber, said valve seat having an aperture formed therein arranged to be closed by the clapper when upon its seat and opened when the clapper is lifted from its seat, and an alarm device operatively associated with said aperture in the valve seat.

In testimony whereof I affix my signature. 125
WILLIAM B. GRIFFITH.
